SANDING CONTROL VALVE

Wayne A. Baldwin, Watertown, N. Y., assignor to
The New York Air Brake Company, a corpora-
tion of New Jersey

Application July 7, 1942, Serial No. 450,059

4 Claims. (Cl. 291—5)

This invention relates to sanding control valves, and particularly to a valve having two sanding push buttons, either of which may be pushed to establish continuous forward or reverse sanding according to the button pressed, and a third push button which may be pushed to terminate sanding initiated by either of the two sanding buttons.

The device is of general utility but was developed particularly to meet the requirements of steam locomotive service. In its preferred form, the sanding valve controls two sanding relay valves, one for forward and the other for reverse sanding, the two relays being differentiated in that one is inactive when its control pipe is vented and operates when the control pipe is charged, whereas the other is inactive when its control pipe is charged and becomes active upon venting of the control pipe. The use of two relays so differentiated is standard practice with applicant's assignee.

In the accompanying drawing, the single figure is a section of the control valve, with the connections to main reservoir, the two relays and the sand traps diagrammed in miniature. Running (non-sanding) positions are shown.

The sectional view of the sanding control valve is diagrammatic to the extent that all the valves are shown on the plane of section. This permits all flows to be traced in a single view, but in actual practice more compact arrangements are possible.

Air for sanding and for operating the controls is supplied through pipe 1 from any suitable source such as the main reservoir (not shown). Branches of line 1 lead to the body 2 of the sanding control valve, and to the relays 3 and 103. The relay 3 is the forward relay and controls cleanout and sanding connections 4 and 5 to forward sand traps 6, one for each rail. The relay 103 is the reverse or backing relay and controls sandtraps 106 through connections 104 and 105.

The forward relay 3 has a control pipe 7 and is equipped with a device 8 which so reverses the characteristic operation of the relay 3 that when control pipe 7 is vented, sanding is stopped, and when control pipe 7 is put under pressure the relay causes sanding. The reverse relay has a control pipe 107 but no device analogous to 8, so that the relay 103 has the normal characteristics which are the reverse of those of relay 3. It suspends action when the pipe 107 is under pressure and starts its sanding cycle when the pipe 107 is vented.

The parts 3 and 103 here merely typify relays which respond oppositely to pressure changes in their control pipes. Since relays so diversified were in use prior to the present invention, and since the details of their construction are here immaterial, the relays will not be described further.

The control of forward sanding is exercised by controlling pressure in chamber 11 in body 2. In this chamber is a double beat valve comprising a supply valve 12 coacting with supply seat 13 and exhaust valve 14 coacting with exhaust seat 15. Supply seat 13 communicates with a branch of port 9 to which main reservoir line 1 leads, and exhaust seat 15 leads to exhaust port 16.

The valves 12 and 14 are nested as shown, and a spring 17 urges both in a direction to close exhaust and open supply. A stem 18 in valve 14 offers a connection through which the valves may be shifted to open exhaust and close supply. Stem 18 is connected with a hub unit 19 clamped to the center of a differential diaphragm unit comprising a smaller diaphragm 21 clamped at its periphery between body 2 and spacer ring 22 and a larger diaphragm 23 clamped at its periphery between spacer ring 22 and cap 24. A spring 25 reacts between hub 19 and cap 24 and acts oppositely to spring 17.

A branch of main reservoir passage 9 leads to space 26 between the diaphragms while space 27 at the inner side of diaphragm 21 is vented to atmosphere around stem 18 to exhaust port 16. Thus main reservoir pressure acting between the diaphragms biases them outward, overpowering spring 25 and permitting spring 17 to close exhaust valve 14 and open supply valve 12. Thus chamber 11 is normally under pressure.

To vent chamber 11, main reservoir pressure is established in chamber 28 within cap 24. This equalizes pressures on the larger diaphragm 23 so that main reservoir pressure urges diaphragm 21 inward, and assisted by spring 25 shifts valves 12 and 14 to open exhaust and close supply so that pressure in chamber 11 falls to atmospheric.

To put chamber 28 under pressure, push button 29 is depressed and unseats the poppet valve 31. This admits main reservoir air from chamber 32, which is connected with a branch of passage 9 to chamber 33, passage 34 and chamber 28.

The reverse sanding control includes parts functionally identical with parts numbered 11 to 34 and such parts are identified by the numerals 111 to 134.

As will be explained further, charging of chamber 28 causes the forward relay to sand continu-

ously, whereas charging of chamber 128 causes the reverse relay to sand continuously. Suspension of either type of sanding requires that chamber 28 or chamber 128 be vented. This can be accomplished by operating a third push button valve, which is connected by a double-seated check valve with whichever chamber 28 or 128 is under pressure.

The double-seated check valve 35 works in a bushing 36 and seats on gaskets 37 and 137 selectively to control communications with extension of ports 34 and 134. Side ports 38 and 138 in the bushing lead via passage 39 to chamber 41. Depression of push button 42 unseats check valve 43 and vents chamber 41 to atmosphere.

Depression of button 29 charges chamber 28 and hence vents chamber 11. Similarly depression of button 129 charges chamber 128 and so vents chamber 111. Either chamber when vented may be recharged by depressing reset button 42.

Chamber 111 is connected directly with control pipe 107, since venting of pipe 107 causes relay 103 to sand.

A different connection is used for the forward relay. Chamber 11 is connected with chamber 44 beneath diaphragm 45, which is clamped by cap 46 over a chamber 47 in body 2. A branch of main reservoir passage 9 leads to chamber 47. A hub 48 at the center of the diaphragm carries a valve disc 49 and a spring 51 biases the hub 48 upward to cause disc 49 to seal on seat 52. This seat 52 controls a passage 53 leading to control pipe 7 and to whistle 54 (used to warn the engineer that sanding is in effect).

When chamber 11 is charged to main reservoir pressure, as normally it is, pressures above and below diaphragm 45 are equal and spring 51 closes disc 49 against seat 52. When button 29 is depressed to charge chamber 28 and vent chamber 11, the diaphragm 45 moves down admitting main reservoir air to control line 7 and blowing warning whistle 54 continuously. This causes forward relay 3 to operate.

If part 8 be omitted, so that relay 3 has the same operating characteristic as relay 103, the parts 44 to 54 may be omitted in which case control pipe 7 must be connected to chamber 11 (just as 107 is connected to 111). The described arrangement is preferred, because it conforms with standard practice. This practice is worked out to give a ready tie-in with electrically-controlled train sanding systems, which operate only for forward sanding.

The use of relays of diverse types is illustrated in the allowed application of Charles A. Campbell, Serial No. 344,148, filed July 5, 1940, since issued as Patent No. 2,291,874, dated August 4, 1942. The sand traps indicated in the present application are the type illustrated in the Campbell Patent No. 2,243,243, issued May 27, 1941.

I claim:

1. In a sanding control valve, the combination of a source of pressure fluid; two pressure motor operated valves one controlling forward and the other reverse sanding; independently operable push-button valves serving when actuated to activate selected ones of said pressure motor operated valves to cause sanding; a push-button operated reset valve; and a pressure-responsive switch valve for connecting said reset valve in active relation with the motor of an active pressure motor actuated valve.

2. In a sanding control valve, the combination of a source of pressure fluid; two pressure motor operated valves, one controlling forward and the other reverse sanding; independently operable push-button admission valves for subjecting the motors of corresponding pressure operated valves to pressure derived from said source; a push-button vent valve; and a double seated check valve for connecting the last-named valve selectively with the motors of said pressure motor operated valves.

3. In a sanding control system, the combination of a source of pressure fluid; two admission and exhaust valves; means biasing said valves to admission position; pressure motors each effective when under pressure to shift its valve to exhaust position; selectively operable valves for subjecting said pressure motors to pressure derived from said source; a reset valve operable to vent pressure; a pressure responsive switch valve subject to pressures in said motors and serving to connect a motor under pressure to the reset valve; and two pneumatic relay valves controlled by respective admission and exhaust valves.

4. In a sanding control system, the combination of a source of pressure fluid; two admission and exhaust valves; means biasing said valves to admission position; pressure motors each effective when under pressure to shift its valve to exhaust position; selectively operable valves for subjecting said pressure motors to pressure derived from said source; a reset valve operable to vent pressure; a pressure responsive switch valve subject to pressures in said motors and serving to connect a motor under pressure to the reset valve; a pressure controlled pneumatic sanding relay valve of the type which becomes active on depletion of pressure, connected to be controlled directly by one of said admission and exhaust valves; a pressure controlled pneumatic relay valve of the type which becomes active upon development of pressure; a pressure responsive valve controlled by the other admission and exhaust valve and serving in response to lowered pressure to admit actuating pressure fluid from said source to the second relay; and a combined whistle and vent serving to bleed actuating fluid from the second relay at a rate less than the capacity of the pressure responsive valve.

WAYNE A. BALDWIN.
